UNITED STATES PATENT OFFICE.

HENRY V. PIAGET, OF JERSEY CITY, N. J., AND FREDERICK A. PIAGET, OF NEW YORK, N. Y., ASSIGNORS TO ROBERT W. PEACH, OF PATERSON, N. J.

RAILROAD-RAIL.

SPECIFICATION forming part of Letters Patent No. 230,811, dated August 3, 1880.
Application filed February 16, 1880.

To all whom it may concern:

Be it known that we, HENRY V. PIAGET, of Jersey City, in the county of Hudson and State of New Jersey, and FREDERICK A. PIAGET, of the city, county, and State of New York, have invented a new and useful Improvement in Railroad-Rails, of which the following is a specification.

The object of our invention is to prevent the noise produced by the vibrations of railroad-rails.

The invention consists in applying a thick layer of cement or like material to the sides and bottoms of the rails, and fastening strips of wood to the sides and bottoms of the rails by means of said cement, thereby preventing the emission of sound by the vibrations of the rails.

In the accompanying drawings, Figure 1 is a cross-sectional elevation on the line *xx*, Fig. 2, of our improvement in rails. Fig. 2 is a side elevation of the same.

Similar letters of reference indicate corresponding parts.

25 The rail A has a strip of wood, B, attached to the inner side by means of some suitable cement H, or like material, which binds the wood and the rail closely together, and will not be cracked or split by the vibrations.

30 The strip of wood B is of such a shape that it fits snugly against the web D, the top of the base E, and the under side of the head F, and does not project out beyond the head, so as not to interfere with the flanges of the wheels.

35 A strip of wood, C, is attached to the outside of the rail A in a similar manner by the cement H; but this strip C is of a greater thickness than the strip B, and lies up snugly against the side and under side of the head F, 40 against the web D and the base E, leaving only sufficient space on the base for the spike-heads to catch.

45 A flat strip of wood, G, is attached to the under side of the base E in the manner described above, but does not extend throughout the length of the rail in one piece, as do the strips B C, but is interrupted at each sleeper, for the rails lie directly on the sleepers, and the strip G is only fastened to the 50 under side of the base between the sleepers.

All of the rail except those parts of head coming in contact with the tread and flange of the wheel and a part of the base sufficient to let the spikes catch is covered with wood and cement, which break all vibratory waves, thus 55 stopping the disagreeable hammering noises which are especially perceptible on bridges or elevated railroads.

The advantage of not covering the entire base is that the spikes can easily be driven in 60 or removed without damaging the wooden strips, and do not require notches cut into the same to receive the spike-heads.

The cements used for connecting the wood and iron are as follows: One consists of dissolved india-rubber, two parts; red lead in oil, three parts; and dissolved glue, four parts; the same being applicable when hot. Another consists of dissolved rubber, four parts; red lead in oil, two parts; litharge, one part; and 70 powdered shellac, one part. This cement is to be applied when cold.

The above proportions are believed to be best; but they may be slightly varied without departing from the principle of our invention. 75

With either of these cements there will be no cracking or breaking under expansion or contraction.

Having thus described our invention, we claim as new and desire to secure by Letters Patent—

1. As an improved article of manufacture, a railroad-rail made substantially as herein shown and described, and consisting of a rail, A, coated with cement, and with the strips of 85 wood B C G attached to the rail by means of said cement, as set forth.

2. The combination, with the rail A, of the strips of wood B and C and the cement H, substantially as herein shown and described, 90 and for the purpose set forth.

3. The combination, with the rail A, of the strips of wood B, C, and G and the cement H, substantially as herein shown and described, and for the purpose set forth.

HENRY V. PIAGET.
FREDERICK A. PIAGET.
